UNITED STATES PATENT OFFICE.

JOHN F. O'CONNOR, OF CHICAGO, ILLINOIS, ASSIGNEE TO WILLIAM H. MINER, OF CHAZY, NEW YORK.

AUXILIARY SHOCK-ABSORBING MEANS FOR DRAFT-RIGGINGS.

1,255,212.

Specification of Letters Patent.

Patented Feb. 5, 1918.

Application filed March 18, 1915. Serial No. 15,343.

To all whom it may concern:

Be it known that I, JOHN F. O'CONNOR, a citizen of the United States, residing at Chicago, in the county of Cook and State 5 of Illinois, have invented a certain new and useful Improvement in Auxiliary Shock-Absorbing Means for Draft-Riggings, of which the following is a full, clear, concise, and exact description, reference being had 10 to the accompanying drawings, forming a part of this specification.

This invention relates to improvements in auxiliary shock absorbing means for draft riggings.

15 An object of the invention is to provide an auxiliary shock absorbing device to be employed in combination with a draft rigging such for instance as a draft rigging of the tandem spring type.

20 Other objects of the invention are to provide an auxiliary friction device which may be readily attached to draft riggings now in service; which is located outside of the space normally used for the draft rigging proper; 25 and which is effective under both buff and draft.

The invention furthermore consists in the improvements in the parts and devices and in the novel combinations of the parts and 30 devices, as herein shown, described or claimed.

In the drawing forming a part of this specification, Figure 1 is a vertical sectional view of a draft rigging showing my improvements in connection therewith, the auxiliary shock absorbing device being shown in section and the yoke, draw-bar and gear proper in side elevation. Fig. 2 is a horizontal sectional view taken substantially on the line 2-2 of Fig. 1, the followers being shown in plan. Fig. 3 is an enlarged transverse vertical sectional view taken substantially on the line 3-3 of Fig. 1. Fig. 4 is a longitudinal horizontal 45 sectional view taken on the line 4-4 of Fig. 3 and Fig. 5 is a transverse vertical sectional view taken on the line 5-5 of Fig. 4.

In said drawing, the center sills are designated by the reference numeral 10 and the same have secured thereto tandem stop castings 11 formed in the usual manner with main stops and limiting stops. The draw-bar 12 is connected to a yoke 13 of the tandem type by any suitable means such for

instance as the engaging shoulders 14 and 15 and the coupler key 16. The yoke 13, as shown, comprises two like loop members 17-17, each of which is provided with front and rear pockets separated by vertical 60 webs or flanges 18-18. Mounted in the two pockets of the yoke members, which are secured together as by bolts 19, are the front and rear shock absorbing means which, in the form shown in the drawing, comprise 65 springs 20 each having an inner and an outer coil and mounted between the usual followers 21-21.

On the inner faces of the vertical webs 18, which together form the intermediate 70 thimble of the yoke, are inwardly extended perforated bosses 22 through which extends a short shaft or pivot 23 and on which is pivotally mounted a lever or pendulum 24, the latter being fulcrumed about its rounded 75 upper end 25 in a plate 26 bolted or otherwise secured to the top flanges of the center or draft sills. Secured to the lower flanges of the center sills is a combined tie and supporting plate 27 bolted as indicated at 80 28 to the flanges, said plate 27 having a longitudinally extending cylinder 29 formed on the under side thereof, said cylinder being open at its rear end and exteriorly threaded to receive a removable cap 30. 85 Mounted within the cylinder 29 is a combined cylindrical friction shell and spring casing 31. Within the latter is contained a spring 32 bearing at its rear end against the rear integral wall 33 of the friction shell 90 and at its forward end against a wedge or spreader 34. The wedge 34 co-operates with a plurality of circularly arranged friction shoes 35 and the latter in turn at their front ends are engaged by a second wedge or 95 spreader 36. In front of the wedge 36 is a pressure block 37 longitudinally slotted as indicated at 38 and within which slot reciprocates the lower end of the lever or pendulum 24. As clearly appears from Figs. 1 100 and 3, the upper and lower arms of the yoke are slotted to permit the lever 24 to swing back and forth therein. Also the plate 27 is provided with an elongated slot 39 on its upper face to permit the movement of 105 the lever and the friction shell 31 is also slotted as indicated at 40 to receive the lower end of the lever 24 therethrough. In normal position of the parts the lever 24 engages the front end of said slot 40 and 110

is permitted only a rearward movement therein, the reason for which will appear hereinafter.

The operation is as follows: The draft rigging proper operates in the usual manner as will be understood and as it is so operated, say under buff, the yoke being moved rearwardly causes the lever 24 to be swung rearwardly about its fulcrum. The lever 24 being thus moved will force the wedge 36 rearwardly and thereby actuate the friction mechanism which includes the shoes, wedges and spring 32. During this operation, the friction shell 31 is held stationary 15 due to its engagement with the cap 30 and the final position of the parts under full buff is as shown in Fig. 4. The parts will, of course, return to normal upon release of the pressure from the draw-bar. Under 20 draft, the lever 24 is swung forwardly by the yoke and this causes the friction shell 31 to be also moved forwardly, the lower end of the lever 24 traveling in the slot 38 of the pressure block 37. During this movement 25 the wedge 36 will be held stationary due to its engagement with said block 37 and consequently the continued movement of the friction shell will bring the friction mechanism into play. Due to the fact that 30 the lever 24 is pivotally connected substantially at its center to the yoke, the movement at the lower end of the lever will be substantially twice that of the yoke. This permits of an auxiliary friction shock absorbing 35 device having a travel of twice that of the gear proper. By varying the position of the pivotal connection between the lever and the yoke, or other part of the gear to which it may be attached, the travel of the 40 lower end of the lever may be varied accordingly.

As will be understood by those skilled in the art, my improvements are not limited to the particular type of draft rigging herein shown and described and various changes and modifications may be made in the auxiliary shock absorbing member and in the manner of actuating it, without in any way departing from the spirit of the invention 45 and all such changes and modifications are contemplated as come within the scope of the claims appended hereto.

I claim:—

1. An auxiliary shock absorbing device 50 for draft riggings comprising a casing, a combined friction shell and spring case slidably mounted therewithin, friction elements coöperable with said shell and a spring mounted in said case.
2. The combination with a tandem spring 55 draft rigging having a tandem yoke provided with an intermediate thimble, of an auxiliary shock absorbing device located

below said rigging and attached to the draft sills, and a lever pivotally connected to said 65 yoke within the thimble thereof and having its upper end fulcrumed and its lower end in engagement with said auxiliary shock absorbing device.

3. The combination with a draft rigging 70 including a yoke and sills, of a combined supporting and saddle plate attached to said sills at the bottom thereof, an auxiliary friction shock absorbing device carried by said plate, a cross plate secured to the tops of 75 said sills, and a lever, said lever being fulcrumed at its upper end with said cross plate, pivotally connected intermediate its ends with said yoke and having its lower end in engagement with said friction shock 80 absorbing device.

4. In an auxiliary shock absorbing device for draft riggings, a saddle plate adapted to extend between and to be attached to a pair of draft sills, said plate 85 being provided with an integral chamber adapted to receive a gear therewithin.

5. The combination with a tandem draft rigging, including a tandem yoke, of an auxiliary shock absorbing device associated 90 with said tandem draft rigging, said shock absorbing device including a friction shell, wedges and friction shoes within the shell, a spring, a casing within which said shell is slidably mounted, and means connected 95 with the yoke for actuating the friction elements when the yoke is moved in one direction and for moving the shell when the yoke is moved in the opposite direction.

6. The combination with a draft rigging 100 having a yoke, of an auxiliary shock absorbing device associated with the draft rigging, said device including a casing having its axis extending horizontally, a shell mounted within said casing, a spring within said 105 shell, friction elements within the shell, and means connected with said yoke extending through said casing and said shell and adapted to engage one of the friction elements.

7. A yoke for draft riggings comprising two loop shaped members arranged side by side, said members being provided with vertical walls substantially at their center to act as a thimble for a tandem gear, said 110 yoke members having their arms notched opposite each other in line with said vertical walls to thereby provide recesses to accommodate a vertical lever or other element extending through the yoke for actuating an auxiliary shock absorber.

JOHN F. O'CONNOR.
